UNITED STATES PATENT OFFICE.

GEORGE VAN BOLT, OF COLUMBUS, OHIO.

RULING-MACHINE.

1,174,365.

Specification of Letters Patent. Patented Mar. 7, 1916.

Application filed February 26, 1915. Serial No. 10,738.

To all whom it may concern:

Be it known that I, GEORGE VAN BOLT, a citizen of the United States of America, residing at Columbus, in the county of 5 Franklin and State of Ohio, have invented certain new and useful Improvements in Ruling-Machines, of which the following is a specification.

The present invention relates to improvements in ruling machines, and is designed especially for use in ruling wax forms to produce matrices to be utilized in the process of electrotyping.

The "case" of wax is properly supported, 15 and its surface is "ruled" by the co-action of the supporting table for the case and a small cutting tool resembling a knife blade or chisel.

The customary manner of producing the 20 lines in the matrix is to have the complete form including the set type, cuts, and all rule set up by the printer from which the matrix or wax mold is produced, and then, by an electrolysis process the electrotype is 25 produced. This process of preparing the electrotype is expensive composition work by the printer, especially on complicated forms of line ruling having lines extending both horizontally and vertically or at right 30 angles to each other in the same form.

By my method and machine, it is necessary only for the printer to set up the type matter and cuts, then from this form a mold is made in wax, after which the lines 35 or rulings are made in the wax as desired.

In the art to which this invention applies, a thin metal slab coated with a wax covering is called a "case," and after the impression is made on the case it is called 40 a "mold" and in the following specification for convenience of description I shall refer to these parts by these terms.

In the accompanying drawings I have 45 illustrated one complete example of the physical embodiment of my invention constructed according to the best mode I have so far devised for the practical application of the principles of my invention.

Figure 1 is a side elevation of the 50 machine complete embodying the novel features of my invention. Fig. 2 is a longitudinal vertical sectional view on line A—A of Fig. 3. Fig. 3 is a top plan view of the machine. Fig. 4 is an end elevation as seen 55 from the left in Fig. 3. Fig. 5 is a transverse vertical sectional view on line B—B

Fig. 6. Fig. 6 is an enlarged detail transverse sectional view on line C—C Fig. 4 showing the traveling carriage for the cutter head. Fig. 7 is a side elevation of Fig. 6. Fig. 8 is a front elevation of the cutter head, detached. Fig. 9 is a top plan view of Fig. 8. Fig. 10 is a vertical sectional view on line D—D of Fig. 9. Fig. 11 is a side elevation of the cutter head of Fig. 8. Fig. 12 is a horizontal, longitudinal sectional view of the tool head on line E—E Fig. 8. Fig. 13 is a detached view of the knob on the cutter or tool head, and Fig. 14 is a plan view of a rack disk on the stem of the 70 cutter or tool head.

In the preferred embodiment of my invention as illustrated in the drawings the machine is adapted to alternately rule lines at right angles to each other *i. e.* by a movement of a reciprocable table longitudinal lines or rules are marked on the wax, and by a transversely movable carriage which is reciprocable the laterally extending lines are marked.

The machine is supported upon the rectangular frame 1 equipped with the four corner legs 2, and as seen in the top plan view (Fig. 3) the top of the frame is open, and at its sides has a pair of rails 3, 3, extending longitudinally of the frame and forming a track way or guide for the longitudinally reciprocable table 4 which is formed with sides or flanges 5, 5, V-shape in cross section. These flanges are adapted 90 to slide in the grooved ways or track rails 3, 3 as the table is reciprocated, and adjacent each end of the frame of the machine a stop block 6 is fixed on the rail to limit the movement of the table. These blocks 95 are slidable on the rails and may be adjusted and held in desired position by set screws 7 in order that the movement of the table may be regulated to determine the length of longitudinal ruling or line drawn 100 in this way.

Located centrally of the table and extending from end to end beneath the same is a rack bar 8 which is fixed to the table in suitable manner as by bolts, and this rack bar is engaged by the pinion 9 to reciprocate the table. The pinion is carried by the transversely extending shaft 10 which is journaled in the sides of the frame as shown in Fig. 5 and projects at one side 110 thereof to accommodate the hand wheel 11 fixed upon its end. By means of the hand

wheel, it will readily be seen, the table may be moved forward and reversed longitudinally of the frame, through the connection with the rack bar of the pinion 5 or rack wheel on the transverse shaft. In this manner the longitudinal movement of the table is produced in order to mark the longitudinally extending rules or lines in the wax.

10 The wax sheet upon which the lines are to be ruled is not shown in the drawings, but when in proper position is laid upon the adjustable table top 12 and by means of the adjusting screws 13 threaded into and 15 through the table proper, the wax sheet or mold may be trued and leveled, and when adjusted to proper position, the set screws 15 in the transverse straps 14 may be used to clamp the mold in place. These straps 20 are supported above the table from the blocks 16, 16 which are of dovetail shape in cross section and slidable in the dovetail grooves 17, 17 in the sides of the table 4, and the blocks may be moved from end to 25 end of the table in these slots, the set screws 18 being used to hold the blocks in fixed position. There are two of the straps 14 shown in the drawings and each strap is provided with four clamping screws, to 30 clamp the mold or case, but it will of course be understood that the number of straps and the number of clamp screws may be varied to suit different conditions.

As before mentioned, the table may be 35 reciprocated through the action of the rack bar and its pinion from the hand wheel, for long and rapid movements. I employ an adjusting mechanism by means of which the table may be moved forward or back, 40 which is designed for short moves and close adjustment of the table to position and comprises a screw bar 19, extending longitudinally of the frame, and journaled for rotation in the cross bracket or arm 20. 45 The bracket 20 as best seen in Fig. 4 has a pair of V-shaped ribs 21 slidable in the V-shaped grooves or ways 3 of the frame 1, and in Fig. 3 it will be seen that the bracket spans the distance between the two rails and 50 is movable with the table when the latter is moved. If it is desired to move the table to adjust it accurately for spacing lines, the screw bar 19 is turned by means of the hand wheel 22, but first the bracket 20 is 55 clamped to the rails 3. This clamping is accomplished by means of the handle 23 and screw 24 the latter threaded through the overhanging side 25 of the bracket. Thus, with the bracket clamped and rigidly 60 held on the rails 3, when the wheel 22 is turned the screw bar is turned in the nut 26 fixed to the table, and the table is moved toward or away from the bracket 20. The nut 26 is preferably a split nut and it may 65 be tightened on the screw bar to take up

wear. When the wheel 11 is used to move the table, the clamped bracket 20 is released from the rails so that it may move with the table and the wheel 22 and screw 19 move with the bracket.

The lateral or transverse ruling device is located above the longitudinal ruling device and suspended above the table by means of the side arms 27 27 attached to the frame and projecting upwardly therefrom. These side arms are connected by means of the transversely arranged channel beam or bar 28, and the side flanges 29 29 of this channel bar have V shaped grooves 30 30 in their upper edges in which the ribs 31 31 of a transverse carriage 32 slide. This carriage is a long bar adapted to reciprocate transversely of the table and its supporting frame and in its movement the carriage is guided in the grooved ways of the channel bar. The carriage is moved through the medium of the screw bar 33 which is supported by end brackets 34, 34 attached to the channel bar 28 and the screw bar may be revolved in these bearing brackets by means of the hand wheel 35 at one end of the bar. The screw bar is adapted to co-act with the threaded nut 36 through which it passes, and this nut, which has a pair of clamping jaws 37, 37, may be moved to adjusted position with relation to the carriage and fixed thereto by means of the clamp screw 38 and its handle 39. When the handle is turned the jaws are clamped on the dovetail rib 40 which is integral with and extends the length of the top of the carriage. This nut is also split and provided with a clamping or set screw 41 which may be turned to take up wear. Thus, with the nut 36 fixed to the carriage, it will be evident that when the hand wheel 35 is turned to revolve the screw bar, the stationary bar will cause the nut to travel and carry with it the carriage, and the latter is made to slide in its guide ways. To limit the movement of the carriage I employ a 100 pair of sleeves 42 42 each of which is movable on the rod 43 supported in the brackets 34 at the ends of the beam 28, and by means of the set screws 44 the sleeves may be secured in adjusted position to stop the 105 movement of the traveling carriage.

The ruling or cutting blade 45 is held to its stem 46 by the nut 47, and this stem is carried by the head 48 which is attached by means of its perforated lugs 49 to the carriage 32 and moves bodily with the carriage when said carriage is moved by power applied to the handle 50 fixed thereto. The cutting blade is movable and adjustable vertically by means of the rack sleeve 51, which incases the stem 46, and the pinion 52 on shaft 53. The shaft may be revolved by the thumb nut 54 on shaft 53 to raise or lower the cutting or ruling tool or blade, and the tool may be held in fixed position by turn- 115 120 125 130

ing a thumb nut 55 on the threaded pin 56 to clamp the split portion 57 of the head about the sleeve (see Fig. 12). The sleeve is prevented from revolving by a key 58, but 5 the stem is designed to be turned or revolved in order that the cutting or ruling blade may be turned to rule lines at different angles. Thus the stem is provided with a knob 59 fixed by the pin 60 at the upper 10 end of the stem and this knob has a lug or finger 61 projecting radially therefrom. At the upper end of the sleeve 51 a head 62 is provided and the knob and head co-act to hold the stem in adjusted position. As best 15 seen in Fig. 14 the sleeve head is a circular disk having four notches 63 any one of which is adapted to receive the finger 61 of the knob 59. The cutter or ruling tool may be turned as desired by first pulling up on 20 the knob 59 against the tension of the spring 64, coiled about the stem between the rack sleeve 51 and the nut 47. The finger of the knob is lifted from its notch, then the stem is turned in the rack sleeve to the desired 25 position, and the spring is permitted to return the stem to extended position, with the finger in the proper diametrically arranged notch 63.

In operating the ruling machine, the wax 30 sheet on its thin metal slab, forming the "case" is first laid upon the adjustable top 12 of the table, and then, by means of the four corner screws 13 in the table, the case is trued into accurately disposed position. 35 The clamping straps 14 and screws 15, are now brought into use and the case is rigidly and firmly secured in place, whereupon the machine is ready for work.

The cutting tool is brought to desired position with relation to the wax sheet by 40 means of the rack sleeve and its pinion, so that its point will mark the wax surface or "rule" the lines. Thus with the cutting blade at its initial point at either side of the 45 table, when the hand wheel 11 is turned the table with its wax sheet is moved under the blade and the blade "rules" a line, to draw the longitudinal line, whereas, to rule the transverse lines, the table is held stationary 50 and the cutting tool is reciprocated by moving the carriage with manual power applied to the handle 50.

In both cases of the screw drive 19 and 55 33, the threads are cut nine to the inch, each thread of course being $1/9$ of an inch or equal to 8 points (type measure). In Fig. 3 it will be noted that the hubs 22' and 35' are graduated or marked into eight parts adapted to register with the index line A on the 60 bearing of the bracket 20 and the other as B on the bearing of a bracket 34. Therefore the space of one graduation on the hand wheels is equal to $1/72''$ or one point (type

measure) travel of the part it is moving. By using this graduation it is comparatively 65 a simple matter to move the cutting tool to position to rule the lines with accuracy and regularity.

The small blocks 6 on the tracks 3 prevent the parts from running off the frame, 70 and in many instances are used to limit travel of the carriage instead of the hand wheel and screw, when running long cuts in the mold, where lines extending entirely 75 across the mold are desired, or where accurate ending or beginning is not desired.

For the same purpose on the transverse cutting or ruling member, the sleeves 42 on the rod 43 are employed. It will be understood that the straps 14 for the clamp screws 80 may be moved the entire length of the table and are adapted to be secured in adjusted position at any point along the table. For extra large cases which practically cover 85 the entire table area, the straps may be turned down at the ends of the table out of the way while the case is being leveled to position preparatory for clamping.

What I claim is:—

1. The combination in a ruling machine 90 with supporting rails, of a work table reciprocable along said rails and a tool for ruling the work in one direction, a bracket 95 slideable on the rails and connected to the table to move therewith and means for clamping the bracket to the rails for holding the table stationary when desired, a beam supported above the table, and means for adjusting said tool with relation to the beam.

2. The combination in a ruling machine with supporting rails, of a work table reciprocable along said rails and a bracket 105 slideable on the rails, a screw bar journaled in the bracket and engaging the table to move said table when the bracket is fixed, means for clamping the bracket to the rails in fixed position, a beam supported above the table, and a tool movable across the table and adjustable with relation to the beam. 110

3. The combination with a supporting frame and rails, of a work table reciprocable along said rails and a bracket supported on said rails, means for clamping the bracket on the rails, a screw bar journaled on the 115 bracket and operatively engaging the table to move the same, a grooved transverse beam supported above the table, a carriage movable on the beam, a tool on the carriage, and means for moving the carriage.

In testimony whereof I affix my signature in presence of two witnesses.

GEORGE VAN BOLT.
